ELECTRIC SWITCH

George J. Meuer, Milwaukee, Wis., assignor to
 Cutler-Hammer, Inc., Milwaukee, Wis., a corporation of Delaware

Application October 4, 1948, Serial No. 52,623

22 Claims. (Cl. 200—6)

1

This invention relates to improvements in electric switches, and more particularly to rotary switches of the slow-make, slow-break type.

An object of the invention is to improve and simplify the construction and operation of switches of the aforementioned character.

Another object is to provide a single form of molded insulating base which may be employed in constructing switches having various different circuit controlling characteristics, nevertheless maintaining a balanced design and construction in the switch.

Another object is to minimize the number of different parts required for construction of switches having such different electrical control characteristics.

Another object is to simplify the relationship of the parts to facilitate assembly and high speed quantity production.

Another and more specific object is to provide an alternating current controlling switch of the aforementioned character which is particularly well adapted for use in conjunction with relatively small sized radio rheostats and the like.

Another object is to provide a switch of the aforementioned character having a diameter no greater than $\frac{1}{8}$ inch.

Another object is to reduce the need for close dimensional control of the relationship between radio rheostats or the like and the switch.

Another object is to provide a switch having a set or sets of contacts which are normally biased to an engaged relation together with simple and efficient means for effecting control of such contacts.

Another object is to provide novel means for actuating such contacts.

Another object is to provide a switch utilizing as a contact actuating element a standardized ball bearing, which as well understood in the art, affords long life and continued close tolerance control over this element, and to provide switch structure affording close control of the tolerances therein notwithstanding minor variations in the relations of the switch parts initially or after considerable wear.

Another object is to provide a switch utilizing a ball bearing as a contact actuating element in which the ball bearing is not required to carry an electrical current.

Another object is to provide a switch of the aforementioned character having a ball-type contact actuator, but nevertheless affording an audible and tactile signal as the contacts are engaged with or disengaged from each other.

Another object is to provide a substantially dust-tight switch of the character aforementioned.

Various other objects and advantages of the invention will hereinafter appear.

2

The accompanying drawings illustrate certain embodiments of the invention which will now be described, it being understood that the embodiments illustrated are susceptible of changes in respect of certain structural details thereof without departing from the scope of the appended claims.

In the drawings, Fig. 1 is a top plan view (triple scale) of a slow-make, slow-break rotary switch of the single-pole type as constructed in accordance with the invention, the switch parts being shown in open circuit position.

Fig. 2 is a center line sectional view on the line 2—2 of Fig. 1, with additional showing of a rheostat and an extension of its shaft in assembled relation with the switch.

Fig. 3 is a bottom plan view of the switch with one bussing lug and rivet therefor shown in dotted lines and additionally showing a pair of lugs illustrating a method of attaching the switch to a radio rheostat or the like.

Fig. 4 is a top plan view of the molded insulating base.

Fig. 4^a is a fragmentary top plan view of a modified form of the molded insulating base illustrating a modification of the cam surfaces.

Fig. 5 is a sectional view of the switch, on line 5—5 of Fig. 1, but showing the switch parts in circuit closing position and additionally illustrating a silver inlay contactor to be used in connection with a solid silver stationary contact rivet for a relatively high rating switch.

Fig. 6 is a top plan view of a modification illustrating a double-pole type of switch, the switch parts being shown in open circuit position.

Fig. 7 is a center line sectional view on the line 7—7 of Fig. 6.

Fig. 8 is a bottom plan view of the double-pole switch illustrated in Figs. 6 and 7.

Fig. 9 is a bottom plan view of a three-wire switch, illustrating a combined connector plate and terminal lug which may be substituted for two of the terminal lugs of the double-pole switch illustrated in Figs. 6 to 8.

Fig. 10 is a top plan view of a modification illustrating a three-way type of switch.

Fig. 11 is a sectional view, on the line 11—11 of Fig. 10.

Referring first to Figs. 1 to 5, inclusive, the numeral 20 designates a molded insulating base of substantially cylindrical form, said base (see Fig. 4) having a substantially cylindrical recess 21 formed therein and opening to the upper surface thereof. Positioned concentrically with respect to main recess 21 and opening to the latter is an auxiliary cylindrical recess 22. Positioned concentrically with respect to recess 22 and opening into the latter is a still smaller cylindrical recess 23, the bottom wall 24 of recess 23 being formed integrally with base 20. Formed

integrally with base 20 and defining the bottom wall of recess 22 and the side wall of recess 23 is an annular portion 25, the upper surface of which slopes gently upwardly from the base of double cam portion 27 in both directions to a meeting point 26 diametrically opposite cam portion 27 as best illustrated in Figs. 2 and 4. Said cam portion 27 has two sloping surfaces 27^a and 27^b and a top surface 27^c, said top surface 27^c being in a plane substantially parallel to but raised from the surface of bottom wall 24 and annular portion 25. Said top surface 27^c of cam portion 27 further has an indentation 27^d preferably of substantially circular contour, the purpose of which will be described hereinafter. Offset upwardly from bottom wall 28 of recess 21 are a pair of flat, preferably horizontal, ledges 29^a, 29^b, and two flat ledges 30 and 31; the surfaces of ledges 29^a, 29^b being in a plane parallel to but higher than the surfaces of ledges 30 and 31, as best illustrated in Fig. 5. A shallow recess 32 is preferably interposed between ledges 29^a and 29^b.

Base 20 is provided with a pair of diametrically opposed external grooves 33^a and 33^b extending downwardly from the upper surface thereof to ledges 20^a and 20^b which are offset upwardly a substantial distance from the lower surface 20^c of said base. Said grooves 33^a and 33^b are adapted to accommodate a pair of lugs 34^a and 34^b which are formed integrally with and extend downwardly from the metal shell 36 of a rheostat 35 of known form as shown, for example, in my prior Patent No. 2,172,397; the inwardly bent lower ends 34^c and 34^d of lugs 34^a and 34^b being shown in Fig. 3. As will be understood, said lugs 34^a and 34^b may form the sole means for effecting attachment of the switch to the rheostat 36.

The top surface of base 20 is also provided with a pair of preferably cylindrical passages 37^a and 37^b extending downwardly through base 20 to ledges 20^d and 20^e, which are offset upwardly a substantial distance from lower surface 20^c of base 20, to accommodate a corresponding number of rivets (not shown) should this method of attachment of base 20 to the shell 36 of rheostat 35 be desired. Formed integrally with the top surface of base 20 are a pair of studs 38^a and 38^b, preferably cylindrical, which may, if desired, be used to assist in insuring against rotary displacement of base 20 with respect to the rheostat shell 36. The top surface of base 20 is also provided with a slightly recessed or downwardly offset portion 39 for a purpose hereinafter described in connection with a modification.

Positioned within recess 22 and adapted to rotate freely therein is a flat punched insulating plate 40 of substantially circular contour. Plate 40 is provided with a centrally located rectangular opening 41, which is adapted to accommodate with a fairly close fit the downward extension 42 of the shaft of rheostat 35 (Fig. 2), it being understood that for this purpose opening 41 is of greater length than breadth. Plate 40 is provided with an opening or peripheral notch 43 of substantially circular contour preferably positioned in radial alignment with the mid-point of one long side of opening 41. Notch 43 is adapted to accommodate a metal ball 44, preferably steel, of relatively small diameter, but nevertheless of greater diameter than the thickness of plate 40. Ball 44 rests on annular portion 25 and is caused to roll upon the surface of the latter and upon one or the other of the cam

portions 27 within the confines of notch 43 as plate 40 is rotated.

Positioned above plate 40 and ball 44 is a resilient metal contactor 45 having an annular intermediate portion 45^a with an outside diameter less than that of recess 22 in which it is positioned, and an inside diameter greater than the length of opening 41 of plate 40 so as to insure mechanical and electrical clearance for shaft extension 42 of rheostat 35 when said extension 42 is positioned within opening 41 of plate 40. Formed integrally with annular portion 45^a but extending outwardly from and offset slightly upwardly therefrom, as best shown in Fig. 5, is a flat horizontal projection 45^b of the relative size and shape best illustrated in Fig. 1. Said flat projection 45^b is adapted to seat on ledge 29^b. Projection 45^b is provided with a perforation to be aligned with a passage 46^a extending downwardly through base 20 from ledge 29^b to the lower surface 20^c of the base to accommodate the hollow-ended shank of a rivet or eyelet 47^a, which shank when upset is adapted to attach flat projection 45^b of contactor 45 to base 20 and to provide electrical conduction from contactor 45 to a suitable terminal lug 48^a positioned on the lower surface 20^c of base 20, as illustrated in Fig. 3; said rivet shank being upset over said terminal lug 48^a, as shown. Seating of flat projection 45^b on ledge 29^b is facilitated by corner portions 49^a and 49^b formed integrally with base 20 and having a slight upward slope, while an inwardly projecting portion 50^a formed integrally with base 20 and extending downwardly from the top surface thereof to bottom wall 28 of recess 21 assists in securing flat projection 45^b against lateral displacement. Shallow recess 32 previously described is provided to accommodate the downwardly bent portion 45^c of contactor 45 where annular portion 45^a joins the flat projection 45^b, to prevent binding of contactor 45 with respect to ledge 29^b of base 20.

Formed integrally with annular portion 45^a of contactor 45 and in diametrically opposed relation to flat projection 45^b is a second projection 45^d of relative size and shape best illustrated in Fig. 1. Projection 45^d extends outwardly from annular portion 45^a and is offset slightly upwardly therefrom as best shown in Fig. 5. Projection 45^d has a downwardly pressed boss 45^e which forms a contact surface for contactor 45. Projection 45^d may also have a metal inlay 45^f of silver or some similar good electrical conductor, as illustrated in Fig. 5, where a switch of relatively high rating is desired.

Ledge 30 is provided with a passage 46^b, preferably circular, extending downwardly through base 20 from ledge 30 to the lower surface 20^c of base 20 to accommodate the hollow-ended shank of a rivet 47^b, the head of said rivet serving as a fixed contact. Rivet 47^b further provides electrical conductivity to terminal lug 48^b positioned on the lower surface 20^c of base 20, as illustrated in Fig. 3, and provides a means for attaching terminal lug 48^b to base 20, rivet 47^b being upset over one arm of terminal lug 48^b as shown. Rivet 47^b may be made of silver or some similar good electrical conductor when used in connection with contact inlay 45^f to provide a switch of relatively high rating.

Terminal lugs 48^a and 48^b are of a well-known L-shaped solder-type, the base portion of each lug preferably having semi-circular aligned notches formed in opposite side edges thereof for engagement with the hemispherical nibs 51^a and

51^b formed integrally with the lower surface **20^c** of base **20** and projecting downwardly therefrom. Said nibs **51^a** and **51^b** in conjunction with the integral downwardly projecting portions **52^a** and **52^b** of the relative size and shape illustrated in Fig. 3 serve to secure terminal lugs **48^a** and **48^b** against substantial rotary displacement relative to the lower surface **20^c** of base **20**. Lower surface **20^c** of base **20** is further provided with similar hemispherical nibs **51^c** and **51^d**, while ledges **29^a** and **31** are provided with preferably circular passages **46^c** and **46^d**, respectively, extending downwardly through base **20** to the lower surface **20^c** of base **20** to accommodate the hollow-ended shanks of rivets similar to rivets **47^a** and **47^b** for attaching bussing lugs if desired, one of which is shown in dotted lines in Fig. 3. Said bussing lugs may be identical with terminal lugs **48^a** and **48^b**. Passages **46^c** and **46^d** as well as passages **46^a** and **46^b** are preferably each provided with a thin integral knockout or diaphragm for closing the same if not used (one of such diaphragms being shown in section within passage **46^b** in Fig. 11), thus to maintain the switch substantially dust-tight when said openings are not used as above described or as hereinafter described in connection with modifications, but may be easily broached if use with bussing lugs and/or additional terminal lugs is desired. Circuit wires may be attached by soldering to the downwardly extended arms of terminal lugs **48^a** and **48^b**.

Contactor **45** is bent downwardly at **45^a** as previously pointed out so that annular portion **45^a** is slanted downward and boss **45^b** is normally touching the head of rivet **47^b** as illustrated in Fig. 5, thus providing a pair of switch contacts biased to a normally closed position and affording a circuit from terminal lug **48^a** through rivet **47^a**, contactor **45**, rivet **47^b** and terminal lug **48^b**. When the insulating plate **40** is rotated ball **44** is caused to roll on the surface of annular portion **25**, up one of the sloping surfaces **27^a** or **27^b** of double cam portion **27**, ball **44** simultaneously pressing upwardly against the lower surface of annular portion **45^a** of resilient contactor **45**, and thus gradually raising contact boss **45^b** from the head of rivet **47^b** until ball **44** comes to rest seated in indentation **27^d** of top surface **27^c** of cam portion **27**, at which point the switch contacts are fully opened as illustrated in Fig. 2. The provision of indentation **27^d** also causes an audible and tactile signal as the switch contacts move to or from fully open position. It is obvious to those skilled in the art that the slow-make and slow-break operation just described will minimize arcing in an alternating current circuit inasmuch as the current will at some time during the relative movement of the contacts pass through zero.

The switch herein illustrated will normally be correlated with radio rheostat **35** so that when ball **44** moves off of cam portion **27**, thus allowing the switch contacts to close, the rheostat **35** will be at its point of highest resistance, while further clockwise rotation of the extension **42** of the rheostat, and hence plate **40** as heretofore described, will move the rheostat progressively into positions of lower resistance until a limit stop, if any, is met. During said rotation ball **44** is prevented from escaping from notch **43** of plate **40** by reason of the gentle upwardly slope of annular portion **25** of which the high point **26** is diametrically opposite cam portion **27**. Thus ball **44** throughout its travel to and from cam **27** has substantially the same clearance from the then downwardly slanting under surface of annular

portion **45^a** of contactor **45**, which clearance is insufficient to allow ball **44** to escape from notch **43** of plate **40**.

It will be understood that the above described use is merely suggestive, the switch being so constructed as to permit either clockwise or counter-clockwise rotation or both, since double cam portion **27** has two sloping surfaces, **27^a** and **27^b** to be used selectively; it being understood that two separate cams to be used selectively might be employed. Similarly, the switch may be used in conjunction with a rheostat or the like without limit stops, thus allowing rotation greater than 360° , though, as well understood, the switch contacts will be opened each time ball **44** or additional similar balls, if used, ride up on cam portion **27** or any additional similar cam portions which may be employed.

In Fig. 4^a is shown in fragmentary top plan view a modification of the molded insulating base illustrating another form of cam which may be provided to afford a smaller arc during which the switch contacts are held open. The reference numeral **120** designates the base as a whole. Within recess **122** and offset upwardly from its annual bottom wall **125** is a cam portion **127** having sloping surfaces **127^a** and **127^b** of the relative size and shape illustrated, and a top surface **127^c**. The top surface **127^c** has a preferably circular indentation **127^d** for seating of ball **44**. The remainder of base **120** is similar to that of base **20**.

The modified form of rotary slow-make, slow-break switch illustrated in Figs. 6 to 8 is of the double-pole type. Molded insulating base **20^x** is the same as base **20** except that the thin integral knockouts of passages **46^c** and **46^d** have been broached to accommodate the hollow-ended shanks of headed rivets **47^c** and **47^d** as will hereinafter appear. Like parts of base **20^x** have been given the same reference numerals as corresponding parts of base **20**.

The double-pole switch is further provided with an insulating plate **40** and a preferably steel ball **44** identical to those employed in the single-pole switch. In lieu of contactor **45** used in the single-pole variety, the double-pole switch is provided with a pair of oppositely curved arcuate resilient metal contactor arms **53** and **54** of the relative size and shape best illustrated in Fig. 6, said arms being formed right- and left-hand from blanks of identical form. End portion **53^a** of arm **53** is seated on ledge **29^b**, corner portions **49^a** and **49^b** and projection **50^a** facilitating said positioning as in the case of the single-pole switch. Rivet **47^a** affords a means of attachment of end portion **53^a** to base **20^x** as well as to provide means for attaching terminal lug **48^a** to the bottom **20^c** of base **20^x**, and at the same time provides electrical conductivity between end portion **53^a** and terminal lug **48^a**. Similarly arm **54** has an end portion **54^a** seated on ledge **29^a**, said positioning being facilitated by corner portions **49^c** and **49^d** and inwardly projecting portion **50^b**. Rivet **47^c** affords a means of attaching end portion **54^a** to base **20^x** as well as to provide means for attaching terminal lug **48^c** to the bottom **20^c** of base **20^x** and at the same time provides electrical conductivity between end portion **54^a** and terminal lug **48^c**.

End portion **53^b** of arm **53** has a downwardly pressed boss **53^c** which forms a contact surface for arm **53**. Said boss **53^c** is positioned to overlie a rivet **47^d**, the hollow shank of which extends downwardly through passage **46^d** and affords means for attaching terminal lug **48^d** to the bottom **20^c** of

base 20^x as well as to provide electrical conductivity between arm 53 and terminal lug 48^d. Similarly end portion 54^b of arm 54 has a downwardly pressed boss 54^c which forms a contact surface for arm 54. Said boss 54^c is positioned to overlie a rivet 47^b, the hollow shank of which extends downwardly through passage 46^b and affords means for attaching terminal lug 48^b to the bottom 20^c of base 20^x as well as to provide electrical conductivity between arm 54 and terminal lug 48^b. Arms 53 and 54 are bent slightly downward at 53^d and 54^d respectively so that bosses 53^c and 54^c make contact with the heads of rivets 47^d and 47^b respectively, thus providing switch contacts biased to a normally closed position. The inner tips 53^e and 54^e of end portions 53^b and 54^b respectively may, if desired, be bent slightly downwardly as shown in Fig. 6.

Interposed between flat plate 40 and arms 53 and 54 is a flat punched insulating plate 55 of such relative size and contour as to allow positioning of said plate 55 within recess 21. More particularly plate 55 has diametrically opposed extended portions 55^a and 55^b which overlie the bottom wall 28 of recess 21, whereas the central portion of said plate has at all points between said extended portions a diameter slightly less than that of recess 22 which recess affords clearance for tilting of plate 55 on the bottom wall 28 of recess 21 as a bearing, as shown in Fig. 7. Plate 55 is provided with a centrally located circular opening 55^c of diameter slightly greater than the length of rectangular opening 41 in plate 40 so as to allow free rotation of the downward extension 42 of the shaft of rheostat 35 (Fig. 2) when said rheostat is attached to the switch as hereinbefore described in connection with the single-pole switch.

As will be understood by those skilled in the art an insulating plate such as plate 55 employed in the double-pole type switch might be used, if desired, in the single-pole switch hereinbefore described, though, of course, the upward offset of projections 45^d and 45^b from annular portion 45^a would be eliminated in this event.

As best shown in Fig. 7, when ball 44 is seated in indentation 27^d of top surface 27^c of cam portion 27, ball 44 will have forced plate 55 upwardly, which plate in turn will be pressing upwardly on the free end portions of contactor arms 53 and 54 simultaneously to maintain both contactor arms disengaged from their cooperating stationary contacts. As ball 44 is moved off of top surface 27^c of cam portion 27 down one or the other of its sloping surfaces 27^a or 27^b, flat plate 55 gradually moves back into a plane substantially parallel with the top of base 20^x, and arms 53 and 54, due to their inherent bias gradually make contact substantially simultaneously with their cooperating stationary contacts through bosses 53^c and 54^c respectively. Thus both arms 53 and 54 are afforded the desired slow-make, slow-break characteristic.

As with the single-pole variety bosses 53^c and 54^c may be provided with a silver inlay as illustrated in Fig. 5 and rivets 47^b and 47^d may be silver or the like to provide a switch of relatively high rating.

In closed position there is electrical conduction from terminal lug 48^a through rivet 47^a, a contactor arm 53, rivet 47^d and terminal lug 48^d similarly in closed position there is also electrical conductivity from terminal lug 48^c through rivet 47^c, arm 54, rivet 47^b and terminal lug 48^b.

In Fig. 9 is illustrated a further modification of

the doublepole switch shown in Figs. 6 to 8, inclusive. In this form provision is made for a three wire switch by substituting for the terminal lugs 48^a and 48^c of the double-pole switch a metal connecting plate 56 of relative size and shape illustrated in Fig. 9 attached to the bottom surface 20^c of base 20^x by rivets 47^a and 47^c. For attachment of circuit wire connecting plate 56 has a lug portion 56^a formed integrally therewith and of the same relative size and shape as the downwardly projecting arms of terminal lugs 48^a, 48^b, 48^c, and 48^d as previously described. Base 20^x is identical to base 20^x except that a part of downwardly projecting portion 52^a has been ground off or omitted as illustrated in Fig. 9 to accommodate connecting plate 56. Connecting plate 56 with its lug portion 56^a thus forms a common terminal for this three wire form of the switch. When the contacts are in closed position electrical conductivity is established from connector plate 56 through rivets 47^a and 47^c, arms 53 and 54, rivets 47^b and 47^d to terminal lugs 48^b and 48^d respectively.

The modified form of rotary slow-make, slow-break switch illustrated in Figs. 10 and 11 is of the three way type. Molded insulating base 20^x is the same as base 20^y except that the thin integral knockout or diaphragm of passage 46^b has been left intact. This form of the switch, similar to the single and double-pole types is provided with an insulating plate 40 and a preferably steel ball 44 which together afford a means for actuating the switch contacts. The three way switch is further provided with a resilient metal contactor 57 having an end portion 57^a of the relative size and shape best illustrated in Fig. 10. End portion 57^a is attached to ledge 29^b of base 20^x by a rivet 47^a the hollow-ended shank of which extends downwardly through passage 46^a and is upset over terminal lug 48^a to secure the latter to the bottom surface 20^c of base 20^x as in the single and double-pole types. Contact 57 further has an annular intermediate portion 57^b formed integrally with and offset downwardly from end portion 57^a so as to fit loosely within recess 22 of base 20^x. Formed integrally with and offset slightly upwardly from annular portion 57^b of contactor 57 are a pair of contact portions 57^c and 57^d extending outwardly from annular portion 57^b at the points thereof respectively as shown in Fig. 10. Contact portion 57^c has a downwardly pressed boss 57^e. Contact 57 is bent downwardly at 57^f so that contact boss 57^e is normally in engagement with the head of a rivet 47^b forming a stationary contact, the hollow-ended shank of said rivet extending downwardly through passage 46^b of base 20^x and being upset over terminal lug 48^d to hold the latter in place on the bottom surface 20^c of base 20^x. Contact portion 57^d overlies ledge 30 of base 20^x and is normally closely adjacent thereto.

The three way switch is further provided with a curved arcuate resilient metal contact arm 58 of the relative size and shape best illustrated in Fig. 10. Arm 58 has an end portion 58^a seated on ledge 29^a of base 20^x and attached thereto by a rivet 47^c the hollow-ended shank of which extends downwardly through passage 46^c of base 20^x and is upset over terminal lug 48^c to secure the latter to the bottom surface 20^c of base 20^x. Arm 58 further is provided with a fingerlike contact portion 58^b of the relative size and shape illustrated in Fig. 10. Contact portion 58^b has a downwardly pressed boss 58^c which overlies contact portion 57^d of contactor 57. The tip of fingerlike contact portion 58^b of arm 58 normally rests on

recessed portion 39 of base 20^c hereinbefore described, so as to be prevented from engaging contact portion 57^d of contactor 57 before contact portion 57^c has disengaged rivet 47^d.

When the switch parts are in their normally biased relationships; that is when ball 44 is not seated on cam 27, electrical conductivity is provided from terminal lug 48^a through rivet 47^a, contactor 57, rivet 47^d and terminal lug 48^d. However, as ball 44 is moved by rotation of plate 40 from annular portion 25 heretofore described up one or the other of the sloping surfaces 27^a or 27^b of cam portion 27 and comes to rest in indentation 27^d on top surface 27^c of cam 27 as illustrated in Fig. 11 said ball 44 presses upwardly on annular portion 57^b of contactor 57 causing contact portion 57^c with its boss 57^e gradually to disengage from the head of rivet 47^d, while simultaneously the raising of contact portion 57^d gradually causes it to engage the boss 58^c of contact portion 58^b of arm 58. Thus in the relationship illustrated in Fig. 11 electrical conductivity is provided from terminal lug 48^a through rivet 47^a, contactor 57, arm 58, rivet 47^c and terminal lug 48^c. The movement of ball 44 on the sloping surfaces of cam portion 27 affords the desired slow-make, slow-break characteristic as hereinbefore described.

The term "rotary" as used in the specification and claims with reference to the switch is to be construed as including any rotary or arcuately movable switch regardless of the degree of such movement.

What I claim to be new and desire to secure by Letters Patent is:

1. In an electric switch of the rotary type, in combination, a contact actuating member having a rolling element loosely mounted therein, means supporting said actuating member for oscillation thereof and affording said rolling element an arcuate track with a cam onto which said rolling element may be driven, and cooperating contacts biased into a given relation and having means through the medium of which the relationship of said contacts is changed by said rolling element when the latter is driven onto said cam, subject to return of said contacts to said given relation upon disengagement of said rolling element from said cam and during progressive movement of said rolling element along said track by continued movement of said actuating member.

2. In an electric switch of the rotary type, in combination, a substantially circular contact actuating member having a ball loosely mounted therein adjacent the periphery thereof, an insulating base affording a bearing for said actuating member in which the latter is oscillatable and affording said ball an arcuate track with a cam onto which said ball may be driven, and cooperating contacts biased to a given relation and having means through the medium of which the relationship of said contacts is changed by said ball when the latter is driven onto said cam, subject to return of said contacts to said given relation upon disengagement of said ball from said cam and during progressive movement of said ball along said track by continued movement of said actuating member.

3. In a relatively small slow-make, slow-break switch of the rotary type, in combination, a substantially circular contact actuating member having a peripheral notch and having a relatively small ball loosely mounted therein, a molded insulating base affording a circular open

bearing for said actuating member in which the latter is oscillatable and tiltable and affording said ball an arcuate track with a cam onto which said ball may be driven, and cooperating contacts biased to a given relation and having means through the medium of which the relationship of said contacts is changed by said ball when the latter is driven onto said cam, subject to return of said contacts to said given relation upon disengagement of said ball from said cam and during progressive movement of said ball along said track by continued movement of said actuating member.

4. In a relatively small slow-make, slow-break switch of the rotary type, in combination, a contact actuating member having a relatively small ball loosely mounted therein, a molded insulating base supporting said actuating member for oscillation thereof and affording said ball a substantially circular track with adjacent oppositely inclined cams onto either of which said ball may be driven according to the direction of movement of said member, and cooperating contacts biased to a given relation and having means through the medium of which their relationship is changed by said ball when the latter rides onto either of said cams, subject to return of said contacts to said given relation upon disengagement of said ball from said cams and during progressive movement of said ball along said track by continued movement of said actuating member.

5. In a relatively small slow-make, slow-break switch of the rotary type for control of an alternating current circuit, in combination, a contact actuating member having a relatively small ball loosely mounted therein, a molded insulating base supporting said actuating member for oscillation thereof and affording said ball a substantially circular track with adjacent oppositely inclined cams onto either of which said ball may be driven according to the direction of movement of said member, said track also having between the high points of said cams an indentation to receive said ball for restraint thereof, and cooperating contacts biased to a given relation and having means through the medium of which their relationship is changed by said ball when the latter rides onto either of said cams, subject to return of said contacts to said given relation upon withdrawal of said ball from said cams and during progressive movement of said ball along said track by continued movement of said actuating member.

6. In a rotary slow-make, slow-break switch, in combination, a steel ball bearing, an insulating member of substantially circular peripheral contour, said insulating member having a non-circular central opening and a peripheral recess arranged in a predetermined relationship to said central opening, said recess having a radial dimension substantially corresponding to the diameter of said ball bearing, said ball bearing being of such size as to project at all times beyond at least one face of said insulating member, an insulating base supporting said insulating member for rotary movement and affording said ball bearing an arcuate track with a cam surface onto which said ball bearing may be driven by said insulating member, and a plurality of cooperating contacts normally biased into a given relationship and having associated means through the medium of which the relationship of said contacts is changed by said ball bearing when the latter is driven onto said cam surface, subject to return of said contacts to said given relation.

tionship upon disengagement of said ball bearing from said cam surface and during progressive movement of said ball bearing along said track as an incident to the aforementioned movement of said insulating member.

7. In a relatively small slow-make, slow-break switch of the rotary type, in combination, an insulating base, a member oscillatably mounted relatively to said base, a ball engaged with said member to be driven thereby in an arcuate path, said base having an arcuate bearing surface for said ball which surface has a cam onto which said ball may be driven by said oscillatable member, a biased member overlying said oscillatable member and said ball to limit outward displacement of both relative to each other and to said insulating base throughout the travel of said ball in its arcuate path, said biased member yielding against its bias to pressure of said ball when driven onto said cam, a stationary contact mounted in said base, and a cooperating contact associated with said biased member to assume different relations with respect to said stationary contact according to the rotary position of said oscillatable member.

8. In a relatively small slow-make, slow-break switch of the rotary type, in combination, an insulating base, a contact actuating member including a plate oscillatably mounted in said base and having an opening therethrough adjacent the edge thereof, and a ball of smaller diameter than that of said opening loosely mounted in said opening, said base having an arcuate track for said ball which track has a cam onto which said ball may be driven by said plate and having the approaches to said cam sloped gently upwardly to a meeting point diametrically opposite said cam, a biased member overlying said plate and said ball cooperating with said sloping track to limit the outward displacement of said plate and said ball relative to each other and to said base throughout the travel of said ball on said track, said biased member yielding against its bias to pressure of said ball when driven onto said cam, a stationary contact mounted in said base, and a cooperating contact associated with said biased member to assume different relations with respect to said stationary contact according to the rotary position of said contact actuating member.

9. In a relatively small slow-make, slow-break switch of the rotary type, in combination, an insulating base, a contact actuating member including a plate oscillatably mounted in said base and having an opening therethrough adjacent the edge thereof, and a ball of smaller diameter than that of said opening but of greater diameter than the thickness of said plate loosely mounted in said opening, said base having an arcuate track for said ball which track has a cam onto which said ball may be driven by said plate and having the approaches to said cam sloped gently upwardly to a meeting point diametrically opposite said cam, a biased member overlying said plate and said ball cooperating with said sloping track to limit the outward displacement of said plate and said ball relative to each other and to said base throughout the travel of said ball on said track, said biased member yielding against its bias to pressure of said ball when driven onto said cam, a stationary contact mounted in said base, and a cooperating contact associated with said biased member to assume different relations with respect to said stationary contact according to the rotary position of said contact actuating member, said biased member having an

opening therein for projection therethrough of an operator for said actuating member.

10. In an electric switch of the rotary type, in combination, a molded insulating base having a main recess opening to the upper surface thereof and including a substantially circular auxiliary recess having a bottom wall providing an arcuate ball track with an upwardly projecting cam portion, a substantially circular flat punched insulating plate fitting within said auxiliary recess to be freely oscillatable in said base, said insulating plate having a peripheral notch, a ball in said peripheral notch to be driven by said plate over said arcuate track and onto said cam portion, a biased member overlying said insulating plate and said ball to limit the outward displacement of both relative to each other and said insulating base throughout the travel of said ball in its arcuate path, said biased member yielding against its bias to pressure of said ball when driven onto said cam, a stationary contact mounted in said base, and a cooperating contact associated with said biased member to assume different relations with respect to said stationary contact according to the rotary position of said insulating plate.

11. In a relatively small slow-make, slow-break switch of the rotary type for control of an alternating current circuit, said switch comprising a molded insulating base having a main recess opening to the upper surface thereof and including a substantially circular auxiliary recess having a bottom wall providing an annular ball track with upwardly projecting oppositely inclined cam portions, a substantially circular flat punched insulating plate fitting within said auxiliary recess to be freely oscillatable in said base, said insulating plate having a peripheral notch, a relatively small ball having a diameter greater than the thickness of said plate in said peripheral notch to be driven by said plate over said annular track and onto either of said cam portions, a stationary contact rigidly mounted in said main recess, and a resilient element mounted in said main recess having a contact portion to cooperate with said stationary contact, said resilient element also overlying said insulating plate and said ball to limit the outward displacement of both relative to each other and to said insulating base throughout the travel of said ball in its arcuate path, said resilient element yielding against its bias to pressure of said ball when driven onto said cam, thereby to move its contact portion relative to said stationary contact.

12. A relatively small slow-make, slow-break switch of the rotary type for control of an alternating current circuit, said switch comprising a molded insulating base having a main recess opening to the upper surface thereof and including a substantially circular auxiliary recess providing an annular ball track with an upwardly projecting cam portion, said track having the approaches to said cam portion sloped gently upwardly to a meeting point diametrically opposite said cam portion, a substantially circular flat punched insulating plate fitting within said auxiliary recess to be freely oscillatable in said base, said insulating plate having a peripheral notch, a relatively small metal ball having a diameter greater than the thickness of said plate in said peripheral notch to be driven by said plate over said annular track and onto said cam portion, a stationary contact rigidly mounted in said main recess, and a resilient element mounted in said main recess, said resilient element having a con-

13

tact portion to cooperate with said stationary contact, said resilient element also overlying said insulating plate and said ball to cooperate with said sloping track to limit the outward displacement of said plate and said ball relative to each other and to said base throughout the travel of said ball on said track and said resilient element yielding against its bias to pressure of said ball when driven onto said cam, thereby to change the relationship of its contact portion with said stationary contact.

13. A relatively small slow-make, slow-break switch of the rotary type for control of an alternating current circuit, said switch comprising a molded insulating base having a main recess opening to the upper surface thereof and including a substantially circular auxiliary recess providing an annular ball track with an upwardly projecting cam portion, said track having the approaches to said cam portion sloped gently upwardly to a meeting point diametrically opposite said cam portion, a substantially circular flat punched insulating plate fitting within said auxiliary recess to be freely oscillatable in said base, said insulating plate having a peripheral notch, a relatively small steel ball in said peripheral notch to be driven by said plate over said annular track onto said cam portion, a stationary contact rigidly mounted in said main recess, and a resilient element mounted in said main recess, said resilient element having a contact portion to cooperate with said stationary contact and having an annular portion overlying said plate and said ball giving access to said plate and cooperating with said sloping track to limit outward displacement of said plate and said ball relative to each other and to said base throughout the travel of said ball on said track and said resilient element yielding against its bias to pressure of said ball when driven onto said cam portion thereby to move its contact portion relative to said stationary contact.

14. In an electrical switch of the rotary type, in combination, a molded insulating base having a main recess opening to the upper surface thereof and including a substantially circular auxiliary recess, said auxiliary recess having a bottom wall affording an arcuate surface with an upwardly projecting cam portion, a contact actuating member comprising a flat insulating plate fitting within said auxiliary recess to be freely oscillatable in said base, said insulating plate having an edge notch and a ball within said notch to engage said arcuate surface, a stationary contact mounted in said main recess, a contactor rigidly secured at one end thereof to said insulating base within said main recess, said contactor having an intermediate arcuate portion and a contact portion in cooperative relation to said stationary contact, and a flat plate of insulating material fitted loosely but non-rotatably within said main recess between said contactor and said contact actuating member so that movement of said ball onto said cam moves said non-rotatable insulating plate against said contactor to cause a change in the relationship of the contact portion of the latter with respect to said stationary contact.

15. In an electrical switch of the rotary type, in combination, a molded insulating base having a main recess opening to the upper surface thereof and including a substantially circular auxiliary recess, said auxiliary recess having a bottom wall affording an arcuate surface with an upwardly projecting cam portion, a contact actuat-

14

ing member comprising a flat punched insulating plate fitting within said auxiliary recess to be freely oscillatable in said base, said insulating plate having an edge notch and a ball within said notch to engage said arcuate surface, a pair of stationary contacts mounted in said main recess, a pair of oppositely curved arcuate contact members of resilient material, each rigidly secured at one end thereof to said insulating base within said main recess, said pair of contact members being in cooperative relation to said stationary contacts, and a flat punched insulating plate fitted loosely but non-rotatably within said main recess between said curved resilient contact members and said contact actuating member so that movement of said ball onto said cam moves said non-rotatable insulating plate against said resilient contact members to cause a change in the relationship of the latter with respect to said stationary contacts.

16. A relatively small slow-make, slow-break switch of the rotary type for control of an alternating current circuit, said switch comprising a molded insulating base having a main recess opening to the upper surface thereof and including a substantially circular auxiliary recess, said auxiliary recess having a bottom wall affording an annular surface with an upwardly projecting double cam, a contact actuating member comprising a flat punched insulating plate fitting within said auxiliary recess to be freely rotatable in said base, said insulating plate having a peripheral notch and a relatively small steel ball within said peripheral notch to engage said annular surface and to be driven onto said cam by clockwise or counter-clockwise rotation of said oscillatable plate, a pair of stationary contacts mounted in said main recess, a pair of oppositely curved arcuate contact members of resilient material, each rigidly secured at one end thereof to said insulating base within said main recess to cooperate with one of said stationary contacts, a flat punched insulating plate fitted loosely but non-rotatably within said main recess between said curved resilient contact members and said contact actuating member so that movement of said ball onto said cam moves said non-rotatable insulating plate against said resilient contact members to move the latter.

17. In an A. C. volume control switch, in combination, a molded insulating base having a main recess opening to the upper surface thereof and including a substantially circular auxiliary recess, said auxiliary recess having a bottom wall affording an arcuate surface with an upwardly projecting cam portion, a contact actuating member comprising a substantially circular flat punched insulating plate fitting within said auxiliary recess to be freely oscillatable in said base, said insulating plate having a centrally located opening to receive a driving part, a peripheral notch and a relatively small ball positioned within said peripheral notch to engage said arcuate surface and to be driven onto said cam portion, a pair of stationary contacts mounted in said main recess, a pair of oppositely curved arcuate contact members of resilient material, each rigidly secured at one end thereof to said insulating base within said main recess to cooperate with one of said stationary contacts, and a flat punched insulating plate fitted loosely but non-rotatably within said main recess between said curved resilient contact members and said contact actuating member so that movement of said ball onto said cam moves said non-

rotatable insulating plate against said contact members to move the latter to assume a different relation to said stationary contacts, said non-rotatable insulating plate being of annular form to render accessible said central opening in said actuating member.

18. In a relatively small slow-make, slow-break switch of the rotary type, in combination, an insulating base, a member oscillatably mounted upon said base, a ball engaged with said member to be driven thereby in an arcuate path, said base having an arcuate bearing surface for said ball which surface has a cam onto which said ball may be driven by said oscillatable member, a resilient member biased toward a given position and overlying said oscillatable member and said ball and having contact portions, and cooperating contacts mounted on said base, one above and one below said resilient member, said resilient member yielding against its bias to pressure, incident to movement of said ball when driven onto said cam and as a function of movement of said ball into and out of engagement with said cam causing its contact portions to assume different relations with respect to said contacts mounted on said base.

19. In a relatively small slow-make, slow-break switch of the rotary type, in combination, an insulating base, a member oscillatably mounted upon said base, a ball engaged with said member to be driven thereby in an arcuate path, said base having an arcuate bearing surface for said ball which surface has a cam onto which said ball may be driven by said oscillatable member, a resilient member biased toward a given position and overlying said oscillatable member and said ball and having contact portions, and cooperating contacts mounted on said base, one above and one below said resilient member, one of the latter contacts comprising an elongated resilient finger fixed at one end to said base and having another point of engagement with said base to limit movement of its contact portion toward said resilient member, said resilient member yielding against its bias to pressure incident to movement of said ball when driven onto said cam and as a function of movement of said ball into and out of engagement with said cam causing its contact portions to assume different relations with respect to said contacts mounted on said base.

20. In an electric switch of the rotary type, in combination, a molded insulating base having a main recess opening to the upper surface thereof and including a substantially circular auxiliary recess having a bottom wall providing an arcuate ball track with upwardly projecting cam portions, a substantially circular flat punched insulating plate fitting within said auxiliary recess to be freely oscillatable in said base, said insulating plate having a peripheral notch, a ball in said peripheral notch to be driven by said plate over said arcuate track and onto either of said cam portions, a resilient member biased toward a given position and overlying said plate and said ball and having contact portions, an arcuate resilient member mounted on said base within said main recess and having a contact portion overlying one of the contact portions of said first mentioned resilient member, and another contact member mounted on said base within said main recess and underlying another contact por-

tion of said first mentioned resilient member, the latter yielding against its bias to pressure of said ball when driven onto said cam and as a function of movement of said ball into and out of engagement with said cam causing its contact portions to assume different relations with respect to said contacts mounted on said base.

21. In an electric switch of the rotary type, in combination, a molded insulating base having 10 a main recess opening to the upper surface thereof and including a substantially circular auxiliary recess having a bottom wall providing an arcuate ball track with an upwardly projecting cam portion, a substantially circular flat punched insulating plate fitting within said auxiliary recess to be freely oscillatable in said base, said insulating plate having a centrally located opening to receive an actuating element, a peripheral notch and a relatively small metal ball in said peripheral notch to engage said arcuate ball track and to be driven by said plate over said arcuate track and onto said cam portion, a resilient member overlying said plate and said ball and having contact portions, an arcuate resilient member 15 mounted on said base and having a contact portion overlying one of the contact portions of said first mentioned resilient member, and another contact mounted on said base and underlying another contact portion of said first mentioned resilient member, the latter having an opening to expose the center portion of said oscillatable insulating plate.

22. A relatively small slow-make, slow-break switch of the rotary type for control of alternating current circuits, said switch comprising a molded insulating base having a main recess opening to the upper surface thereof and including a substantially circular auxiliary recess providing an annular ball track having an upwardly projecting cam portion, and having the approaches to said cam portion sloped gently upwardly to a meeting point diametrically opposite said cam portion, a substantially circular flat punched insulating plate fitting within said auxiliary recess to be freely oscillatable in said base, said insulating plate having a peripheral notch, a relatively small steel ball in said peripheral notch to be driven by said plate over said annular track onto said cam portion, a resilient element mounted in said main recess overlying said plate and said ball and having contact portions, an arcuate contact member mounted on said base and overlying one of the contact portions of said resilient element, and another contact 35 mounted on said base and underlying another contact portion of said resilient member, said resilient member overlying said plate and said ball to cooperate with said sloping track to limit outward displacement of said plate and said ball relative to each other and to said base throughout the travel of said ball on said track.
